(57) **CLAIM**

The ornamental design for a gemstone sorting gauge, as shown and described.

DESCRIPTION

FIG. 1 is a front view of a gemstone sorting gauge of my new design;
FIG. 2 is a rear view thereof;

FIG. 3 is a top view thereof;

FIG. 4 is a bottom view thereof;

FIG. 5 is a left view thereof;

FIG. 6 is a right view thereof;

FIG. 7 is a front perspective view thereof; and,

FIG. 8 is a rear perspective thereof.

The present claim relates to the ornamental design of a gemstone sorting gauge. The gemstone sorting gauge is used to measure and sort gemstones.
